MOUNTING FOR ROCK DRILLS

Filed Aug. 25, 1927

FIG.-3.

FIG.-1. FIG.-2.

INVENTOR.
Charles C. Hansen.

BY *Herbert G. Gudur*
HIS ATTORNEY.

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

MOUNTING FOR ROCK DRILLS.

Application filed August 25, 1927. Serial No. 215,366.

- This invention relates to rock drills, but more particularly to a mounting for supporting a plurality of rock drills of the drifter type.
- 5 The objects of the invention are to enable a pair of rock drills to be supported in parallel spaced relation with respect to each other, to enable such rock drills to be advanced and retracted from the work as a unit, and to 10 facilitate the operation of drilling and minimize the expense thereof whenever the work requires a series of closely spaced drill holes along a straight line, as for instance, in quarrying operations in which it is desired 15 to remove the rock in dimension blocks.

The usual form of procedure in removing rock by means of broaching steels is to first drill a series of closely spaced holes and after the desired number of holes have been 20 drilled, to substitute broaching steels for the drill steel and thereby cut away the walls between adjacent holes. Heretofore, however, this method of quarrying has been confined largely to cuts in which the drilling 25 apparatus could be maintained in substantially a vertical position, as the apparatus which has made this type of quarrying possible has been found to be inadequate for severing the rock along a vertical face. The 30 present invention is particularly though not exclusively adapted to support the drills in the positions necessary for forming such cuts and contemplates the use of a suitable mounting clamped to the drills and cooperate 35 slidably with the usual type of rock drill shell and its feed screw, whereby the mounting together with the drills may be advanced and retracted with respect to the work.

40 In the drawings illustrating the invention and its mode of application,

Figure 1 is a partial end elevation and partly in section of the mounting.

Figure 2 is a longitudinal sectional elevation taken through Figure 1 on the line 2—2 looking in the direction indicated by the arrows, and

Figure 3 is a plan view of the mounting partly in section taken through Figure 2 50 on the line 3—3 looking in the direction indicated by the arrows.

Referring to the drawings in which is illustrated a practical application of the invention, A and B designate a pair of rock 55 drills of the drifter type having the usual

feed screw lugs C. On opposite sides of the feed screw lugs C are located the guide ribs D which extend longitudinally of the cylinder E. The rock drills A and B may be of any conventional type in which the cylinder E, a front head F and a back head G and other parts comprising the casing of the drill are held securely in operative position by a pair of spring pressed side bolts H disposed on opposite sides of the drill. 60

In the front head F is disposed a drill steel J and at the rearward end of the back head are indicated the water tube parts K which may be of any well known type for introducing cleansing liquid through the drill steel J, thence into the drill hole for removing the detritus therefrom. 65

In accordance with the present invention, means are provided for supporting the rock drills A and B in parallel spaced relation 70 with respect to each other and in such manner that both drills may be advanced towards the work as a unit. These means comprise a carriage designated by L having a body portion O on each side of which are a 75 pair of lateral bearings P. The bearings P may be suitably spaced with respect to each other to accommodate the particular size and type of drills for which the mounting is intended and these bearings in the present instance are provided with grooves Q for the reception of the guide ribs D carried by the rock drill cylinders E. 80

Suitable means are provided for clamping the feed screw lugs C firmly against the 90 rearward bearings P. These means consist in the present instance of a plate R of such proportions as to enable said plate to overlap and engage the rearward ends of both of the feed screw lugs C. The plate R has an aperture S for the reception of a bolt T which extends through a lug U on the rearward end of the carriage body O. A nut V is threaded on the rearward end of the bolt T to clamp the plate R securely against the lugs 100 C and consequently the drills A and B against movement with respect to the carriage L. 105

In order to enable the carriage L to be suitably supported and guided by a rock drill shell W, the body portion O of said carriage is provided on opposite sides with longitudinal guide ribs X adapted to slide in guideways Y of the shell W. At the rearward end of the body portion O and preferably 110

underneath said body portion is formed a feed screw lug Z substantially like the feed screw lugs C of the drills A and B. Accordingly the feed screw lug Z is provided with an aperture b to receive a feed screw nut c locked in position by a nut d threaded on the rearward projecting end of the feed screw nut c. The interior of the feed screw nut c is suitably threaded to cooperate with a feed screw e for effecting relative longitudinal movement between the carriage L and the shell W. The shell W and the feed screw e may be of a well known type in which the feed screw is supported rotatably in front end of the shell and carries at its rearward end a crank handle (not shown) whereby the feed screw e may be manually rotated.

In assembling the device, the rock drills A and B may first be placed on the bearings P in such a manner that the guide ribs D will be in slidable engagement with the grooves Q. In this position of the rock drills, the feed screw lugs C will lie rearwardly of the rearward bearings P which they will abut in the assembled position. With the drills thus disposed on the carriage L, the plate R may be placed in position to lie against the rearward surfaces of the feed screw lugs C. Thereafter, the nut V may be threaded on the bolt T to press the plate R firmly against the feed screw lugs C and thus clamp the carriage L and the rock drills A and B securely against relative movement.

After the rock drills and the carriage have been assembled in the manner described, the assembly may be placed in the shell W so that the guide ribs X of the carriage L will be in slidable engagement with the guideways Y of said shell. By thus arranging these parts, the feed nut c will be in the correct position to receive the feed screw e in the usual manner. The apparatus will then be in readiness for use and may be mounted on a suitable column or other support for the purpose described.

I claim:

1. A mounting for a plurality of rock drills, comprising in combination with cylinders having lateral projections, a carriage, bearings on the carriage to support the drills, and a common clamping means pressing on the projections to hold the drills against movement with respect to the carriage.

2. A mounting for a plurality of rock drills, comprising in combination with cyl-

inders having feed screw lugs, a carriage, bearings on the carriage to support the drills, and common means acting on the feed screw lugs to clamp the drills to the carriage. 60

3. A mounting for a plurality of rock drills, comprising in combination with cylinders having guide ribs and feed screw lugs, a carriage, bearings on the carriage to support the drills, said bearings having grooves to interlock with the guide ribs, and common means acting on all the feed screw lugs to clamp the drills securely to the carriage. 65

4. A mounting for a plurality of rock drills, comprising in combination with cylinders having guide ribs and feed screw lugs, a carriage, lateral bearings on the carriage having grooves to interlock with the guide ribs for holding the drills in parallel spaced 70 relation with respect to each other, a plate bearing on the feed screw lugs, and means carried by the carriage acting on the plate to clamp the feed screw lugs securely between the bearings and said plate. 75

5. A mounting for a plurality of rock drills, comprising in combination with cylinders having guide ribs and feed screw lugs, a carriage, lateral bearings on the carriage having grooves to interlock with the guide 80 ribs for holding the drills in parallel spaced relation with respect to each other, a plate bearing on the feed screw lugs, means carried by the carriage acting on the plate to clamp the feed screw lugs securely between the bearings and said plate, and guide ribs on the carriage slidably cooperating with the guideways of a rock drill shell. 85

6. A mounting for a plurality of rock drills, comprising in combination with cylinders having guide ribs and feed screw lugs, a carriage having an aperture for the reception of a feed screw nut, lateral bearings on the carriage having grooves to interlock with the guide ribs for holding the 90 drills in parallel spaced relation with respect to each other, a plate bearing on the feed screw lugs, means carried by the carriage acting on the plate to clamp the feed screw lugs securely between the bearings and 95 said plate, and guide ribs on the carriage slidably cooperating with the guideways of a rock drill shell. 100

In testimony whereof I have signed this specification.

CHARLES C. HANSEN.
